E. O. KRENTLER

LAST

Original Filed April 24, 1922

Fig. 1.

UNITED STATES PATENT OFFICE.

EDWIN O. KRENTLER, OF DETROIT, MICHIGAN, ASSIGNOR TO KRENTLER-ARNOLD HINGE LAST COMPANY, OF DETROIT, MICHIGAN, A CORPORATION OF MICHIGAN.

LAST.

Application filed April 24, 1922, Serial No. 556,150. Renewed September 15, 1926.

The present invention is an improved form of hinge last and is directed to improve and perfect the hinge type of last.

In the manufacture of hinge lasts it is necessary and important to provide a last construction which will be of great strength and yet with as few parts or members and also with as little cutting away or weakening of the wood part of the lasts as is possible. To this end important features of my present construction consist in providing a hinge last with only three members, when considered in its simplest form, these members consisting in a metallic hinge member secured to the forepart, a second metallic hinge member secured to the heel part, and a combined locking and unlocking member united and assembled with the hinge parts on a common pivot. Preferably I utilize a spring in connection with the operation of the locking and unlocking member, but such spring is not essential, as will be more fully explained hereafter.

In my copending application, Ser. No. 553,616, filed April 17, 1922, I have illustrated, described and claimed a type of hinge last wherein the metallic hinge members were rigidly and firmly interlocked by the interposition of a movable third or locking member and said locking member was removable by the operation of a fourth member, i. e., an operating lever. In my present invention I have greatly improved and simplified the construction of this type of last, while carrying out all the objects of my invention described and claimed in said prior and copending case, by eliminating one of the elements above noted, and in the present invention I have formed both the locking member and the releasing instrumentality as a single element.

In the present invention also I have combined the advantageous features of the well-known type of hinge last such as is illustrated in Patent 1,094,153, dated April 21, 1914, as well, also, as Patent 1,410,477, dated March 21, 1922, having herein utilized my combined locking, releasing and movable element in a construction wherein the metallic last parts are concealed and protected and but a minimum amount of the wood of the last—and that in the central, firm part of the wood—is cut away to receive the hinge members. Furthermore the present

invention is readily applicable to the "knuckle joint" or "kant-break" type of hinge last without injury to the strength of the same or the functions or features thereof.

A still further feature of great importance, and which I believe is distinctly novel in the present invention, is that by the employment of a spring the locking element is automatically locked during the mere operation of extending the last, and also simultaneously and by virtue of such spring action, any looseness or wear in the pivot and unlocking parts, as well as in the connections between the hinge members and the respective forepart and heel part to which they are attached, is taken up, and the last is locked in as firm and secure a manner and position, it is unlocked as easily as when the parts are all new and in their original working condition.

Further features of the invention, novel combinations of parts and advantages will be hereinafter more fully pointed out and claimed.

Referring to the drawings, illustrating a preferred embodiment of the invention,

Fig. 1 is a side view partly in cross-section, illustrating my improved last in extended position;

Fig. 2 is a view also partly in cross-section illustrating the last in flexed or broken position;

Fig. 3 is a fragmentary cross-sectional view on the line 3—3 of Fig. 1; and

Fig. 4 is a cross-sectional view on the line 4—4 of Fig. 1.

Referring to the drawings, 1 illustrates the forepart and 2 the heel part of a typical form of wooden last, as shown in the said prior patents and my copending application, preferably divided by a line of cut giving the interlocking knuckle joint effect as shown by the projecting portion 3 on the heel part 2 and the abutting bearing faces 4 and 5 to resist strains and stresses bottomward, the last being normally, in shoe manufacture, in upside down position. In the forepart 1 is bored a recess 6 to receive a tubular member 7, the latter being secured therein by a rivet or bolt 8. In the heel part is also formed a recess 9 in which a plate 10 is fitted and secured by a rivet 11. A tube 7 and plate 10 overlap, the tube

having a slot to receive the overlapping or projecting portion of said plate 10, and the same are united by a pivot 12 passing through the knuckle projecting 3, and on which pivot the forepart and heel part of the last are hinged for relative movement. The heel plate 10 has a forwardly extending projection 15, working through the slot in the forepart of the tube 7. This tubular member 7 is also formed with the slot portion open at the top slightly, as illustrated at 16, 16, Fig. 4, and straddling the heel plate hinge member 10 is my combined locking, operating and unlocking device. This device consists in a metallic hinge member comprising a pair of arms or lugs 17, 17, suitably spaced to straddle the heel plate 10, being united at the outer or top portion 20 and also at the forward part 21. The latter may be and preferably is formed as a block or bolt of suitable diameter to fit slidably the tube 7, and may be integral with the arms 17, 17, or secured thereto by a rivet 22. The arms 17, 17, are preferably formed in substantially triangular or V-shaped contour, extending downwardly each side of the plate 10 and about the projection 15, thus holding the locking portion 21 forwardly of the pivot 12, each of said arms 17 having slots 24 through which the pivot 12 passes.

In the forepart 1, I cut or form a kerf 25 of sufficient depth and width to receive the locking and unlocking devices so far as the width of the arms 17, 17, is concerned, when the same is moved forwardly, the latter sliding on the pivot 12.

With the last constructed as thus far described, and in extended position as shown in Fig. 1, a slight pressure on the handle portion 20 of the locking and unlocking device will act to slide the same forwardly for the limit allowed by the length of the slot 24 and the diameter of the pivot 12, thus moving the interlocking portion 21 out from under engagement with the overhanging projection 15 on the heel plate 10, thereupon permitting the heel and foreparts to be readily flexed. Upon repositioning the last in extended position, a slight movement of the locking and unlocking device or member rearwardly or to the right viewing the figures in the drawing, serves to catch the portion 21 under the part 15 and lock the same bearing between the lower part of the tube 7 and said part 15 of the heel plate. The lower contacting face of this projection 15, where it engages the portion 21, may be and preferably is slightly beveled, to permit a tightening action between the contacting faces in the locking action, when the device is moved to the right, viewing the figures and therefore into locked position. This permits compensation for looseness and wear and holds the lower faces 4 and

5 always firmly in contact, irrespective of a slight looseness in the hinge parts or wear in the rivets.

In order to make the locking action automatic as well as to facilitate the action of the same, and as well, also, as to maintain the parts in firm and rigid position, I provide a coiled spring 30, fitting within the tubular member 7 and bearing between the rivet 8 and the interlocking portion 21 of the locking and unlocking device.

This spring 30 acts normally and constantly to force the locking and unlocking device and particularly the portion 21 forwardly and hence when it is in engagement with the projection 15, the last will be held under a tightening tension, the space 31 being cut back considerably to allow for such continuous tension during a considerable extent of such looseness in the wear of the last parts.

In assembling the last the fittings are readily applied and connected, the tubular and plate hinge members being fitted and pinned as is usual in this type of last. Thereupon the locking and interlocking member is applied, straddling the hinge plate 10, the spring 30 is fitted if a spring is desired, and the parts are joined and the pivot pin 12 driven in, thereby automatically securing the fore and heel parts together, as well as the locking and interlocking member, said pin passing through the slot 24 therein.

The operation of the last will be readily understood from the foregoing description and is identical with that of my said copending application. The last is easily unlocked by a simple pressure on the portion 20 of the locking and unlocking device, thereby releasing the locking engagement of the portion 21 from its position, when the last is extended as shown in Fig. 1, and thereupon the forepart and heel part are readily flexed and the last can be removed from the shoe. Reverse movement of the hinge parts automatically locks the last in extended position, when a spring is employed, or if a spring is not employed, a slight reverse movement of the locking and unlocking device serves to move the portion 21 into locked engagement.

I believe that my present invention wherein a last is devised and constructed by a process which permits the uniting of the forepart, heel part, and hinge members simultaneously with the assembling and permanently securing of a locking and unlocking element is new, and I wish to claim this process of manufacture broadly herein, this particular feature being common with the last of my present invention and my copending application Ser. No. 553,616, filed April 17, 1922.

My invention is further described and defined in the form of claims as follows:

1. A two-part last, having hinge connecting means uniting said parts, an element

mounted on the hinge connecting means and movable relatively therewith and automatically movable to interlock therewith to lock the last rigidly in extended position, and to 5 release said interlocking action at will.

2. A two-part last having hinged means comprised of two members to unite said parts while permitting a relative pivotal movement between said parts, a combined 10 locking and unlocking element, cooperating with said hinge means, and movable longitudinally of said hinge means, cooperating with both said hinge members to interlock therewith and to hold the last in rigid 15 extended position, said element having a handle portion to control locking or unlocking at will.

3. A two-part last having hinged means comprised of two members to unite said 20 parts while permitting a relative pivotal movement between said parts, a combined locking and unlocking element, cooperating with said hinge means, and movable longitudinally of said hinge means, cooperating 25 with both said hinge members to interlock therewith and to hold the last in rigid extended position, the engaging portions of 30 said interlocking members being constructed and arranged to compensate automatically for looseness between the last parts.

4. A two-part last having hinged means comprised of two members to unite said parts while permitting a relative pivotal movement between said parts, a combined 35 locking and unlocking element, cooperating with said hinge means, and movable longitudinally of said hinge means, cooperating with both said hinge members to interlock therewith and to hold the last in rigid 40 extended position, the engaging portions of said interlocking members being constructed and arranged to compensate automatically for looseness between the hinge members.

5. A two-part last having hinge members 45 uniting said parts, in combination with a locking and unlocking element movable longitudinally of said hinge members to lock or unlock the last at will.

6. A two-part last having hinge members 50 uniting said parts, in combination with a locking and unlocking element movable longitudinally of said hinge members to lock or unlock the last at will, said element having a handle portion to effect the longitudinal movement.

7. A two-part last having hinge members 55 uniting said parts, in combination with a locking and unlocking element movable longitudinally of said hinge members to lock or unlock the last at will, said element hav-

ing a handle portion to effect the longitudinal movement in one direction, and yielding means to actuate said element in a reverse direction.

8. A two-part last, having hinge members 65 uniting said parts to permit relative pivotal movement, a combined locking and unlocking element mounted on the pivotal connection of said members, having a portion extending on one side of said pivot to 70 constitute the interlocking device and a portion extending on the opposite side of said pivot to provide an operating handle.

9. A two-part last, having hinge members 75 uniting said parts to permit relative pivotal movement, a combined locking and unlocking element mounted on the pivotal connection of said members, having a portion extending on one side of said pivot to 80 constitute the interlocking device and a portion extending on the opposite side of said pivot to provide an operating handle to afford releasing of the interlocking portion.

10. A two-part last having hinge members 85 uniting said parts for relative pivotal movement, one of said hinge members being formed hollow, a combined locking and unlocking element, having one portion adapted to slide within said hollow hinge member, and a handle portion to effect said sliding action, whereby the last may be rigidly 90 locked in extended position and said lock released before flexing the last.

11. A two-part last having hinge members 95 uniting said parts for relative pivotal movement, one of said hinge members being formed hollow, a combined locking and unlocking element, having one portion adapted to slide within said hollow hinge member, and a portion guided on the other hinge 100 member, together with a handle portion to effect said sliding action, whereby the last may be rigidly locked in extended position and said lock released before flexing the last.

12. A two-part last having hinge members 105 uniting said parts for relative pivotal movement, one of said hinge members being formed hollow, a combined locking and unlocking element, having one portion adapted to slide within said hollow hinge member, and a portion straddling the other hinge member, and slotted to be held in assembled position by the pivot pin uniting 110 said hinge members, and means permitting interlocking and releasing.

In testimony whereof, I have signed my name to this specification.

EDWIN O. KRENTLER.
